UNITED STATES PATENT OFFICE.

MONTRAVILLE M. WOOD, OF SCHENECTADY, NEW YORK, ASSIGNOR TO
GENERAL ELECTRIC COMPANY, A CORPORATION OF NEW YORK.

FUNNEL.

No. 838,489.

Specification of Letters Patent.

Patented Dec. 11, 1906.

Application filed February 23, 1905. Serial No. 246,890.

To all whom it may concern:

Be it known that I, MONTRAVILLE M. WOOD, a citizen of the United States, residing at Schenectady, county of Schenectady, State of New York, have invented certain new and useful Improvements in Funnels, of which the following is a specification.

This invention relates to funnels for use in filling vessels with liquid. Its object is to enable a mixture of two liquids to be thoroughly separated and the two elements caused to pass through different outlets.

The invention is especially advantageous in separating out the water that is frequently found in commercial gasolene and which causes a great deal of annoyance to the consumer, especially in the case of automobiles driven by explosive-engines.

The funnel which forms the subject-matter of my invention is provided with a diaphragm or screen of fine wire-netting, through which the liquid is poured. The netting is of such fineness of mesh that when the gasolene wets the netting it is impervious to water, while, on the other hand, the gasolene or similar lighter fluids will not be retained by it. It is well known that water and oil are not diffusible and that water contained in gasolene or other oil settles to the bottom of the containing vessel. Hence in pouring off the contents of the vessel gasolene will flow off first and thoroughly wet the netting as it passes through, so that the netting becomes practically an oiled surface which though perforated excludes water, but permits the gasolene to pass. At one side of the funnel is an escape-opening through which the water can flow off, so as to avoid clogging the funnel. I also prefer to provide a float-indicator, which will rise when the vessel or tank is nearly full and give warning of that fact.

In the accompanying drawings, Figure 1 is a top plan view of a funnel embodying my invention, and Fig. 2 is a diametrical cross-section of the same.

The body 1 of the funnel is made of any suitable material, such as sheet metal, and may be corrugated, if desired, to give it greater stiffness. The body is bowl-shaped and has the usual downwardly-projecting spout 2 at its lowest point. Near the top of the funnel is arranged a screen or diaphragm

3, preferably of wire-netting of fine mesh. This diaphragm extends entirely across the funnel and is held in place by any suitable means, such as a ring 4, around which the netting is secured and which fits snugly into the funnel. An additional ring or hoop 5 may be placed inside the ring 4, if desired, to aid in securing it, and lugs 6 may project in from the rim of the funnel over the ring 4 as an additional fastening. An escape-opening is provided at one side of the funnel, preferably having a spout 7 passing through the rings and the side of the funnel just above the netting and proceeding in a downward direction, as shown. Just below the escape-opening is fixed a shelf 8, preferably a segment-shaped piece of sheet metal lying above the netting, as shown. At some convenient point a small vent 9 is formed through the netting.

When a float-indicator is provided, there is an eyelet 10 inserted at the center of the netting, through which passes an upright rod 11, whose lower end is attached to a float 12 and whose upper end carries a flange 13 to cover the eyelet and a weight 14 to keep the rod normally in place.

The operation of my invention is as follows. The spout 2 is inserted in the filling-orifice of a tank or other vessel with the float depending therein, and the funnel is preferably slightly inclined, so that the spout 7 is at the lowest point. The gasolene or other liquid is then poured upon the netting, which strains out all the water and foreign liquid or solid ingredients, permitting only the pure gasolene to pass through into the lower part of the funnel and thence to the tank. The vent 9 allows the air under the netting to escape. The water retained by the netting flows off through the spout 7 and is thus prevented from accumulating in the funnel, so that all danger of clogging the device is obviated. When the tank is nearly full, the float begins to rise, and thus warns the operator that the supply of gasolene must be stopped.

What I claim as new, and desire to secure by Letters Patent of the United States, is—

1. A funnel having a fine-mesh diaphragm, and means for the escape of liquid retained by said diaphragm.
2. A funnel having a diaphragm of fine

wire-netting, and a spout leading off just above the same.

3. A funnel having a diaphragm of fine wire-netting, a shelf covering one side of said diaphragm, and a spout leading off just above said shelf.

4. A funnel having a diaphragm of wire-netting, an escape-opening at one side of the funnel just above said diaphragm, and a

float-indicator passing through said dia- phragm.

In witness whereof I have hereunto set my hand this 21st day of February, 1905.

MONTRAVILLE M. WOOD.
